(57) **CLAIM**

The ornamental design for a display screen with transitional graphical user interface, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a first image in a sequence for a display screen with transitional graphical user interface showing a first embodiment of my new design; FIG. 2 is a front view of a second image thereof; FIG. 3 is a front view of a third image thereof; FIG. 4 is a front view of a first image in a sequence for a display screen with transitional graphical user interface showing a second embodiment of my new design; FIG. 5 is a front view of a second image thereof; and, FIG. 6 is a front view of a third image thereof.

The broken line at the periphery of the figures illustrate a display screen, and the remainder of the broken lines illustrate portions of the transitional graphical user interface. None of the broken lines form part of the claimed design. Shading in FIGS. 4-6 depicts contrasts in appearance of the transitional graphical user interface. The appearance of the animated image sequentially transitions between the images shown in FIGS. 1 through 3 and FIGS. 4 through 6, respectively. The process or period in which one image transitions to another forms no part of the claimed design.
